(57) **CLAIM**

I claim the ornamental design for a slotted turner, as shown and described.

DESCRIPTION

FIG. 1 is a rear view of a slotted turner of the claimed design; FIG. 2 is a bottom view of the slotted turner shown in FIG. 1;

FIG. 3 is a front view of the slotted turner shown in FIG. 1; FIG. 4 is a left side view of the slotted turner shown in FIG. 1;

FIG. 5 is a front, left, top perspective view of the slotted turner shown in FIG. 1;

FIG. 6 is a right side view of the slotted turner shown in FIG. 1; and,

FIG. 7 is a top view of the slotted turner shown in FIG. 1. The ornamental design that is claimed is shown in solid lines in the drawings.

1 Claim, 7 Drawing Sheets
